UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

ACTUATING MECHANISM FOR PRESSING MACHINES

Application filed April 10, 1931. Serial No. 529,052.

This invention relates to pressing machines and particularly to actuating mechanism for garment or laundry pressing machines.

Various types of actuating mechanism have been devised for garment and laundry pressing machines with a view of obtaining a type of actuating mechanism which will work equally well on thin or thick work and with various thicknesses of padding on the buck. A result sought in such types of actuating mechanism is to obtain heavy pressure by the use of a minimum amount of working fluid, and to avoid the necessity of follow-up adjustment to compensate for changes in the thickness of the work or padding.

A modern type of actuating mechanism which has proved itself quite successful is commonly known as the pry-bar or cam-bar actuating mechanism and includes a toggle which moves into position over one end of a pry-bar as the pressing element moves into light contact with the work. The position of the toggle with respect to the pry-bar will depend on the thickness of the work and the depression of the padding but provision is made to boost the toggle, by means of the pry-bar, regardless of the position of the toggle when the pressing elements are in light contact. In the past considerable difficulty has been experienced due to the fact that the bearing surfaces between the toggle and pry-bar have been necessarily so shaped that line contact only was obtained when boosting the toggle and due to the tremendous pressures exerted the line contact caused ridges to form in the bearing face of the pry-bar and these ridges seriously interfered with the efficient operation of the actuating mechanism.

The principal object of this invention is to provide a pressing machine having actuating mechanism of the pry-bar type in which the engaging surfaces of the actuating mechanism are mounted so that they have surface contact, during the entire boosting operation, regardless of the thickness of the work or the padding on the buck. A further object of the invention is to provide a bearing member or shoe for engaging with the pry-bar mechanism, and to mount the bearing member on an equalizing mounting so that it is held in nor-

mal position by springs but it is shiftable to automatically obtain surface contact with the pry-bar mechanism regardless of the relative position of the bearing member and the pry-bar mechanism when the press is closed under 55 light pressure.

A further object of the invention is to provide a pry-bar mechanism having a replaceable bearing face which may be conveniently removed and a new bearing face substituted in the event of damage or serious wear materially affecting the bearing face so as to impair its efficient operation. A further object of the invention is to provide an actuating mechanism of the pry-bar type in which 60 a booster-bar is operated from a pry-bar through novel motion transmitting mechanism.

Other objects and advantages of the invention will appear and will be pointed out as the 65 description proceeds.

The invention consists in the novel features and in the combinations and constructions hereinafter set forth and claimed.

In describing this invention reference is 70 had to the accompanying drawings in which like characters designate corresponding parts in all the views.

Figure 1 is a diagrammatic side elevation, partly in section, of a pressing machine embodying the invention.

Figure 2 is an enlarged fragmentary view, partly in section, of a portion of the actuating mechanism shown in Figure 1.

Figure 3 is a view along the line 3-3 of 75 Figure 2.

Figure 4 is an enlarged view of a portion of the mechanism shown in Figure 3.

Figure 5 is a section along the line 5-5 of 80 Figure 4.

Figure 6 is a section along the line 6-6 of 85 Figure 4.

The invention is shown as applied to a pressing machine having a movable pressing element or head 11 carried by a yoke 12 which is pivotally mounted at 14 on a pressing machine frame 16. The head 11 is movable into and out of pressing relation with a fixed pressing element or buck 18 which is mounted on a neck 20 supported by the pressing 90

machine frame. The yoke 12 is pivotally connected at 22 with a link 24 which is pivotally connected at 25 with an extendible link 26. The extendible link 26 is pivotally connected at 28 with the pressing machine frame 16, and a forwardly extending arm 30, formed on the lower end of the link 26, is connected with a counterspring 32. The upper end of the spring 32 is connected at 34 with the pressing machine frame 16. The links 24 and 26 form a toggle and the counterspring 32 normally holds the toggle in broken position so that the pressing elements will be out of contact and the press open.

15 A fluid motor 36 is oscillatably connected at 38 with the pressing machine frame 16. A piston rod 40, of the fluid motor 36, is pivotally connected at 42 with the upper end of the link 24, or may be connected directly 20 to the yoke 12. When working fluid is supplied to the fluid motor 36, the piston rod 40 will be actuated to move the yoke 12 and bring the head 11 into light pressure contact with the buck 18 thus moving the press into 25 preliminary closed position.

Heavy pressure is applied to the pressing elements by means of pry-bar mechanism. This pry-bar mechanism includes a booster-bar 46 which is pivotally connected at 47 with 30 the pressing machine frame 16. The booster-bar 46 is operated by a pry-bar 48 which is pivotally connected at 50 with the pressing machine frame 16. A fluid motor 52 is oscillatably mounted at 54 on the pressing 35 machine frame and is pivotally connected at 56 with the pry-bar 48. A spring 58, connected at its lower end with the pry-bar 48 and at its upper end with the pressing machine frame, normally holds the pry-bar in 40 raised position as shown in Figure 1.

One end of the pry-bar 48 is formed as a yoke 60 and straddles the booster-bar 46. A roller 62 is mounted between the two sides of the yoke 60 and contacts with the lower 45 side of the booster-bar 46.

When working fluid is supplied to the fluid motor 52 the pry-bar 48 will be actuated about its pivotal connection 50 and the roller 62 will operate to raise the end 50 of the booster-bar 46 and thus apply heavy pressure to the pressing elements in a manner later to be described.

The booster-bar 46 is provided with a bearing portion 64 which is held in position by 55 suitable means such as screws 66. The bearing face of the bearing portion 64 is preferably in the form of a groove having sloping sides as shown in Figure 3 and this groove is in the form of an arc about the pivot point 28 as a center, as shown in Figure 2.

Referring to Figures 4 and 5 it will be noted that the lower end of the link 24 threads into the side of the short shaft 68. A bearing member 70 is rotatably mounted on the short shaft 68. The link 24 extends through

a slot 72 in the bearing member 70 and due to the fact that this opening is in the form of a slot it is possible for the bearing member 70 to rotate through a considerable angle on the shaft 68 before the ends of the slot 70 72 strike against the link 24. Lugs 75 are provided on the bearing member 70 and these lugs are preferably formed with recesses 76 for receiving springs 78. Screws 80, which are threaded into the lugs 75 along the axis 75 of the recesses 76, assist in holding springs 78 in proper position.

The upper end of the link 26 is provided with members 82 which are spaced apart a sufficient distance to receive the shaft 68 between them as shown in Figure 4. Screws 84 are threaded into the members 82 and engage the shaft 68 along its axis to provide the pivotal connection between the links 24 and 26. Since the pivotal connection between the links 24 and 26 is never subject to much strain the screws 84 engaging recesses in the ends of the shaft 68 provides a satisfactory pivotal connection. Lugs 85 are provided on one of the members 82 in position 80 to engage the springs 78.

Since the lugs 85 are an integral part of the members 82, which are provided on the upper ends of the link 26, it will be obvious that the bearing member 70 will normally be held in line with the link 26. When the booster-bar 46 is operated to boost the bearing member 70 and link 24 the springs 78 will permit the bearing member 70 to rotate on the shaft 68 as much as necessary to permit the bearing member 70 to remain in surface contact with the booster-bar 46. The lower side of the bearing member 70 is provided with a wedge-shaped bearing face designed to fit the groove in the bearing portion 64 of the booster-bar 46. This bearing member 70 thus provides in effect a floating shoe having surface contact with the booster-bar 46 at all times during heavy pressure 100 operation.

Since the link 26 is pivotally connected at a fixed point 28 with the pressing machine frame it is necessary to provide means by which the toggle may be extended during the operation of the booster-bar 46. Such extension is provided by a housing 90 with which the lower portion of the link 26 has telescopic engagement. A spring 92 normally holds the link 26 in shortened position and a collar 94 mounted on the lower portion of the link 26 limits the extent to which the spring 92 may thrust the lower portion of the link 26 into the housing 90. Preferably the members 82 are formed integral with the housing 90, these parts being shown in the drawings as a single casting or forging. This particular means of forming an extendible toggle link forms no part of the present invention.

The operation of the machine is as follows:—

When the operator wishes to close the press he will admit working fluid to the fluid motor 36 so that the piston rod 40 will be actuated to move the pressing head 11 into light contact with the buck 18. During this movement of the pressing head into preliminary closed position the toggle consisting of the links 24 and 26 will move toward straightened position and the link 24 together with the floating shoe or bearing member 70 will move into position over the end of the booster-bar 46.

When the operator wishes to apply final heavy pressure he will admit working fluid to the fluid motor 52 which will move the pry-bar 48 in a clockwise direction about its pivotal mounting 50 so that the roller 62 will raise the end of the booster-bar 46 and bring the face of the bearing portion 64 into contact with the bearing face of the floating shoe or bearing member 70. It will be obvious that if the work on the buck is thick the toggle will not move as far toward straightened position in which case the bearing member 70 will have moved only a slight distance over the bearing portion 64. If the work or the padding on the buck is thin the toggle will move much nearer to straightened position and the bearing member 70 will move further along the bearing portion 64.

Since the face and the arc of travel of the bearing member 70 and the curve of the face of the bearing portion 64 are both about the same pivotal connection 28 as a center, it will be obvious that the clearance between the bearing member 70 and the bearing portion 68 will remain the same regardless of how close the toggle approaches to straightened position. When the end of the booster-bar 46 is raised to apply heavy pressure to the pressing elements the booster-bar 46 will move about its pivotal connection 47. This movement of the booster-bar 46 will cause the face of the bearing portion 64 to shift so that its center of curvature no longer coincides with the pivotal connection 28. The bearing member 70 is mounted so that it may also shift and always maintain its surface contact with the face of the bearing portion 64. Due to the area of surface contact between the bearing faces of the bearing member 70 and the bearing portion 68 there is no danger of ridges being formed in the face of the bearing portion 64 due to excessive pressure when the mechanism is operated to apply heavy pressure to the pressing elements.

The invention is illustrated in its preferred embodiment but changes and modifications may be made without departing from the spirit of the invention as set forth in the appended claims.

What I claim is:

1. In a pressing machine, cooperating

pressing elements, one of which is movable toward and from the other; mechanism for effecting the applying of pressure to the pressing elements including a pry bar having a bearing surface extending lengthwise thereof; and motion transmitting means between the pry bar and the movable element including a member, connections between it and the movable element, said member being arranged at an angle to the pry bar, and a shoe pivotally connected to said member and slideable along the bearing surface on the pry bar upon preliminary closing of the press and making and maintaining surface contact with said pry bar during operation of the pry bar.

2. In a pressing machine, cooperating pressing elements, one of which is movable toward and from the other; mechanism for effecting the applying of pressure to the pressing elements including a pry bar having a bearing surface extending lengthwise thereof; and motion transmitting means between the pry bar and the movable element including a member, connections between it and the movable element, said member being arranged at an angle to the pry bar, a shoe pivotally connected to said member and slideable along the bearing surface on the pry bar upon preliminary closing of the press and making and maintaining surface contact with said pry bar during operation of the pry bar; and means for resisting relative pivotal movement of the shoe and the member.

3. In a pressing machine, cooperating pressing elements, one of which is movable toward and from the other; mechanism for effecting the applying of pressure to the pressing elements including a pry bar having a bearing surface extending lengthwise thereof; and motion transmitting means normally out of engagement with the pry bar and movable into engagement therewith by a preliminary closing of the press; said motion transmitting means including a yoke for carrying the movable pressing element, a link pivotally connected at its upper end to the yoke, and a shoe pivotally connected to the lower end of said link and having a bearing surface complementary to and coacting with the bearing surface on the pry bar.

4. In a pressing machine, cooperating pressing elements, one of which is movable toward and from the other; mechanism for effecting the applying of pressure to the pressing elements including a pry bar having a bearing surface extending lengthwise thereof; and motion transmitting means normally out of engagement with the pry bar and movable into engagement therewith by a preliminary closing of the press; said motion transmitting means including a yoke for carrying the movable pressing element, a link pivotally connected at its upper end to

the yoke, a shoe pivotally connected to the lower end of said link and having a bearing surface complementary to and coacting with the bearing surface on the pry bar, and means for resisting relative pivotal movement of the shoe and the link.

In testimony whereof, I have hereunto signed my name, at Syracuse, in the county of Onondaga, and State of New York, this 10 30th day of March, 1931.

ERNEST DAVIS.
